PRINTING MEMBER FOR INTAGLIO OR
ROTARY PHOTOGRAVURE PRINTING

August A. Leuchter, Augusta, Maine

Application April 17, 1928, Serial No. 270,639

5 Claims. (Cl. 101—401)

Intaglio or rotary photogravure printing is mostly done from cylindrical surfaces, each of such cylinders chiefly consisting of an iron core, mounted upon a steel shaft, and carrying on its outer periphery a layer of copper, which when ground and polished to perfection, is etched upon, and serves then as the actual printing-surface of such cylinders.

Usually such layers of copper are produced by electrolytic deposition directly upon the iron body or core of such cylinders, and are carried to a thickness suitable for receiving from twenty to thirty etching in succession. Under the general proceedings of carrying out the successive etchings upon said outer layers of copper, it is customary to remove an etched-in-surface, bearing images to be reproduced by what is known as "gravure" or intaglio-printing, by the process of grinding and afterwards re-polishing the face of said layer of copper in order to receive the next etching.

Under this commonly general procedure the diameter of such printing-cylinders is being constantly reduced for such successive etchings, and it is not possible therefore to retain any fixed standard diameters of cylinders, except a ground-off outer section, which had carried a previous etching, were re-built, and thus the cylinder brought back to its former diameter by an additional deposit of copper.

Since it is highly desirable to maintain a fixed standard diameter for such printing cylinders, and to avoid the process of grinding-off used printing surfaces, and gradually re-finishing the newly exposed copper surface to make it suitable for receiving a new etching thereon, but at the required expenditure of from eight to ten hours of time and effort, different means have been suggested and devised to dispose of such used printing surfaces, and to replace them in much shorter time by new deposits of the same thickness, thereafter made ready to receive a new etching.

One of such means, embodies a method whereby a thin layer of copper is deposited upon the cylinder body without becoming solidly attached to the same, except at the two extreme ends of the cylinder, but otherwise forming a loose detachable shell extending all over the periphery of the cylinder, which feature enables the removal of such a shell by shaving or cutting through the two extreme solidly connected ends of the same, whereupon such shell can be readily removed from the cylinder body by peeling, after a lengthwise incision is made in the same. To

bring about such condition of a substantially disconnected electrolytic deposit, the cylinder body is purposely prepared in such a way, by either oxidizing its surface or otherwise laying on an interference film, that the growing-fast of such an on-coming electrolytic deposit to the cylinder body is positively prevented in the process of electro-deposition.

While such and other similar methods possibly offer certain advantages by producing a readily detachable shell-like deposit, and do facilitate the stripping-off of the deposit whenever its removal is desired, certain distinct disadvantages are entailed by such methods, inasmuch as a printing surface, and especially an intaglio one, should have an absolute tight and solid connection throughout with the underlying cylinder-body, because in the process of printing from such a cylinder, commonly known as rotogravure printing, considerable pressure is exerted by the impression-roller against the etched surface of the printing cylinder in order to force the paper, passing between them, most thoroughly down into the depressions of the etchings, in order to receive the full value of tone-gradation by the varying density of ink carried in the etched-in images of the printing surface.

Since best results can only be had in intaglio or rotary photogravure printing by exerting considerable pressure against the printing-cylinder, it is clearly obvious that a loosely laid-on shell, without any intimate and solid connection with the underlying cylinder-body, can not present an ideal printing surface, considering the press operation alone, but other and greater objectionable features are present when the etching and preparation of the printing surface in general is carried out.

In such latter operation, in order to get best effects, considerable retouching, tooling, re-engraving and the like are commonly practiced, and must be resorted to, and such work is naturally more safely and practically carried out on a solidly connected layer of copper than on a loose shell, where there is always danger of cutting-through in any operation of hand-tooling, or the loosening of such a shell in spots by burnishing, or by having any ink work its way underneath through any possible pores in such a shell-deposit, and eventually may cause a loosening or buckling of such deposit in the process of printing.

It is for this reason that such method of preparing and producing of printing surfaces by means of a detachable shell has not met with

approval and is more or less objected to when cylinders for intaglio-printing in color are to be prepared, involving far more exacting conditions and more retouching in order to reach desired effects in the varying depths of the etching.

Therefore it is one purpose of the present invention to overcome and eliminate all such objectionable features and deficiencies entailed by the practice of a loosely laid-on shell-deposit to 10 form the actual printing surface of a cylinder, and to produce by a different proceeding a printing surface of an electrolytically deposited layer of copper of suitable thickness to receive and carry an intaglio etching; but such layer of copper is so intimately and tightly deposited onto 15 another layer of a hard metal, which forms the outer periphery of the cylinder body, that removal of the deposited layer of copper is not possible by any mechanical stripping method, but could only be accomplished by either grinding, or turning-off in a lathe, or else by electrochemical dissolution in an electrolyte, or by other chemical disintegration in reconverting the metallic copper into a copper-salt or oxide.

While I have under my newly devised method of producing removable printing surfaces, either cylindrical or flat, a choice of three distinctly different ways to effect such removal, I prefer the one of electro-chemical dissolution as the most practical and economical one, whereby I am enabled to re-deposit the copper-layer from the cylinder surface back onto the anode plate, thus saving from eighty to eighty-five per cent. of the originally deposited copper, that is, of the layer first deposited to form the printing surface on the cylinder; and naturally such saving of copper repeatedly takes place every time a used printing-surface is removed to become replaced by a new deposit.

With such objects in view, my invention consists of novel features in the printing member, such as cylindrical or flat, and in certain process steps, to be hereinafter described and then claimed, with reference to the accompanying drawing, illustrating the invention as preferably applied to a printing cylinder, and in which:

Figure 1 is a longitudinal section before the copper deposit is formed, and

Fig. 2 is a similar section after the deposit has been made.

In the drawing, a steel shaft 5 has the core 6 of the printing cylinder mounted and fixed therein in suitable well known manner. This is but one form of printing cylinder to which the invention may be applied.

To make the removal of a used printing surface possible by electro-chemical dissolution of the copper, and in this way convert it back onto the anode-plate, it is necessary to carry on the cylinder body 6, and to constitute the base for the final layer of copper forming the actual printing surface, a layer 7 of hard metal, capable of receiving and mechanically and intimately combining with the on-coming electrolytic deposit at the time such final layer 8 of copper is grown thereon by electro-deposition; and also on the other hand, when the removal of such body 8 of copper is undertaken by electrolytic action, said layer 7 of hard metal must also be capable 70 of resisting corrosion and dissolution in the electrolyte under the influence of the reversed current, when this layer 7 of hard metal must then actually serve as an insoluble anode, and remain immune to any reaction of both the current as well as the copper-electrolyte usually em-

ployed. The electrolyte is the usual acid copper bath. The speed of rotation of the cylinder during electro-chemical treatment may approximate 200 revolutions per minute, for example.

Since a used intaglio printing surface naturally consists of an unevenly-thick layer 8 of copper, due to the fact that the same carries the etched-in images of varying depths, it follows that in the course of electrolytic dissolution the etched-in sections of such layer of copper become dissolved first, by reason of being thinner, thereby exposing the layer 7 of hard metal underneath in those sections, and which now must remain unaffected, while gradually the copper is being dissolved completely all over, the thicker sections taking the longest.

When all traces of the copper layer 8 have disappeared, and the layer 7 of hard metal is now completely exposed, it is only necessary to break the reversed current connection, under 20 which the cylinder had been made the anode-terminal, and the anode-plate been the cathode-terminal in the electrolyte, and after brushing the cylinder with the hard metal layer, all bare on its outer surface, clean from any scum or foam 25 of a gaseous formation, a new deposit may be formed again immediately, by throwing the reversible current switch back into its normal position, when thereby normal current connections become reestablished in the depositing-tank, and 30 the cylinder is made again the cathode-terminal in the depositing solution, and copper-depositing proceeds again onto said layer of hard metal 7 until the desired thickness of copper layer 8 is 35 reached, which latter is determined by the amperage-amount of current flowing in a given period of time.

As this layer of hard metal remains entirely unaffected by any reaction of either current or depositing solution, no change in size of cylinder 40 body will take place, thereby assuring standardizing sizes of cylinders, which under the old method of grinding off the used printing surfaces and thereafter re-finishing, to facilitate etching-on of new printing-images, was not possible, but causes 45 constant reducing of cylinder sizes with every new etching effected thereon.

Summing up the foregoing it becomes evident that the outstanding feature of this invention is an absolutely solid and perfectly united non- 50 stripping layer of copper on the outer surface of a cylinder body, whereon all the usual operations of etching, retouching and tooling, as become necessary in the preparation of intaglio printing surfaces, may be carried out with utmost security 55 and no danger of causing the said thin layer of copper to come loose or lift from the cylinder body; neither would any amount of pressure in the printing operation have any detrimental stretching effect on same, nor could even a local 60 grinding operation effect a loosening of its hold on the underlying body.

In making an individual deposit for every etching, only a thin layer is necessary, requiring at best only polishing; and due to the fact that the 65 removal of the used printing face can be accomplished by electrochemical dissolution, and thereby the layer of copper be transferred from the cylinder back onto the anode-plate, and as the same would be repeated with every renewal of the 70 printing face of a cylinder, a great saving of copper is realized especially in the continuous run. For example, the thickness of the copper may be from three to six thousandths of an inch, and the hard base preferably thicker.

All such achievements are solely due and possible only by the creation of a layer 7 of hard and impervious metal completely encasing the iron core 6 of the cylinder body, or such other layers of 5 softer metals the latter may consist of, and be directly underneath and adjacent to the final layer of copper, which has to serve as the actual printing surface of a cylinder.

The evident purpose of this layer 7 of hard 10 impervious metal, preferably consisting of nickel, or a combination thereof to increase the corrosive resistance, is to form a permanent base for the layer of copper constituting the actual printing surface, with which it must most intimately unite; 15 but also on the other hand the base layer 7 must serve as a positive protection against corrosion and disintegration of the cylinder body, of which it is a most vital part, when dissolution of the copper layer is enacted and carried out by the 20 electro-chemical process for the purpose of removing a used printing surface.

In creating such a layer 7 of impervious hard metal the invention is not confined to the employment of nickel, but there could be used any other 25 metal capable of resisting the corrosive action of the copper electrolyte combined with the influence of the reversed electric current, under which condition the cylinder-body actually becomes the anode-terminal, and must then assume 30 all properties of an insoluble anode, as soon as any etched sections of the copper-layer have yielded to electro-chemical dissolution, and the layer of the impervious metal underneath becomes exposed, since it is only in such way that the disintegration 35 of the cylinder-body below said final layer of copper is positively prevented, and thus a permanent unaffected base for said outer layer of copper is created.

Other metals of like corrosion resisting property 40 that might be considered for such purpose would be chromium, platinum and also lead, but it is preferred not to use either of these for the reason of being highly expensive, as is the cost of platinum, or a perfect union with the final layer of 45 copper is not possible, but might only be used when a detachable copper-shell is desired with a view of stripping or peeling-off bodily; and finally a layer of lead is at best only a very soft body and very difficult to maintain in perfect physical condition, especially when considering that one principal requirement of this invention is the creation 50 of a hard impervious layer of metal, capable of being brought to a true and high finish and so maintained during the continuous practice of 55 building-on and taking-off said layers of copper, serving as printing-surfaces of cylinders.

Besides, layers of such other metals are difficult 60 to produce in the required thickness but answer at best for a light plating only, which would prove useless for this purpose, because, while in such state they might temporarily resist the corrosive action of the copper electrolyte, they could not resist the powerful influence of the electric current passing through the cylinder body as an 65 anode and outwardly therefrom towards the cathode surface, and due to which tendency there is caused a loosening and lifting-up of any such lightly plated film or pellicle of the respective metal, and then of course, the cylinder-body 70 would no longer represent an insoluble anode, but be subject to attack and disintegration, thereby ruining the same, and making the whole operation of removing such an outer copper-film a complete failure.

75 This very same tendency prevails in creating

this necessarily hard and impervious layer of metal by the use of nickel, or a combination thereof with traces of chromium or platinum injected; there also it is obligatory to deposit a heavy enough layer of such metal; so that the pushing and pulling power of the electric current passing through the cylinder-body and on towards the cathode surface, in its very act of dislodging and dissolving said copper layer by electrolytic process, has no longer any such ruinous effect on the 10 layer of nickel.

It is evident therefore that whichever corrosion resistance metal is used for creating such an impervious metallic layer, the same must be carried to such thickness that the powerful influence of 15 the reverse flowing current can have no loosening or lifting influence on such a layer, and cannot disturb the same in the least.

Therefore it is preferred to create such impervious metallic layer of nickel, as that is reasonable in cost, and the electro-deposition of the same can be carried to any desired and almost unlimited thickness with ease, and furthermore nickel possesses great tensile strength besides hardness, and may be turned or ground true, and 20 also brought to a high surface-finish, which it is 25 apt to retain due to its hard and non-corrosive nature, and in general it is the ideal metal for this very purpose.

The encasing of the cylinder-body with nickel 30 is even carried to far greater thickness than it is necessary to resist any detrimental current action, for the reason that it affords and brings about greater rigidity of the cylinder-body, usually consisting of cast iron and copper, and thereby prevents any sinking of sections of the cylinder 35 periphery, and in general helps to keep the cylinder in perfect shape and true condition.

What I claim as new, is:

1. A printing member having a permanent base 40 of hard, impervious, non-corrosive metal, and a thin outer layer of a different kind of metal for providing a rotary photogravure printing surface and which throughout its entire area is intimately and solidly united with such base, and which layer 45 is of a character suitable for etching such printing surface, the outer layer being sensitive to electrolytic dissolution of its metal and the metal of the base being neutral thereto.

2. A printing member, including a main body, 50 a layer of hard, impervious, non-corrosive metal intimately united with the body, and forming a permanent base, and an exterior thin layer of softer metal for providing a rotary photogravure printing surface and which is intimately and 55 solidly united throughout with such base, and which exterior layer is of a character suitable for etching such printing surface, the exterior layer being sensitive to electrolytic dissolution of its metal and the metal of the base being neutral thereto.

3. A printing member, including a main body, a layer of hard, impervious, non-corrosive metal 60 intimately united with the body, and forming a permanent base, and an exterior thin layer of copper for providing a rotary photogravure printing surface and which throughout is intimately and solidly united with the base by electro-deposition, and which exterior layer is of a character 65 suitable for etching such printing surface, the exterior layer being sensitive to electrolytic dissolution of its metal and the metal of the base being neutral thereto.

4. A printing cylinder, including a core, a shaft 70 on which it is fitted, a layer of hard, impervious,

- non-corrosive metal extending all over the cylindrical surface and ends of the core, and an exterior layer of copper intimately united with the layer of hard and non-corrosive metal by electro-
5 deposition throughout the whole surface area of the hard, non-corrosive layer, and the cylindrical surface of the copper layer being of a character suitable to provide a rotary photogravure printing surface.
10 5. A printing member having a main body with

a permanent nickel base electro-deposited thereon, and an exterior thin layer of copper directly electro-deposited on the base, and which deposited layer of copper has a depth slightly more than sufficient for one etching, and is of a character suitable to provide a rotary photogravure printing surface and throughout is intimately and solidly united with the outer surface of such base, the base being the harder of the two metals. 5
